UNITED STATES PATENT OFFICE.

WILLIAM S. MILLS AND HECTOR E. BISAILLON, OF BRIDGEPORT, CONNECTICUT.

STOP-MOTION DEVICE.

Application filed July 21, 1922. Serial No. 576,484.

To all whom it may concern:

Be it known that we, WILLIAM S. MILLS and HECTOR E. BISAILLON, citizens of the United States, residing at Bridgeport, in the 5 county of Fairfield and State of Connecticut, have invented or discovered certain new and useful Improvements in Stop-Motion Devices, of which the following is a specification, reference being had therein to the 10 accompanying drawing.

This invention relates to an automatic stop motion device for sewing machines or the like, and which is set into action by a knot or lump in the thread before such knot 15 or lump arrives at a point where it might cause damage, as by causing a breakage of the thread or bending of the needle when such knot or lump reaches the needle of a sewing machine. The present invention relates 20 to certain improvements on the stop motion devices covered by our U. S. Patents No. 1,359,266, dated November 16, 1920, No. 1,380,003, dated May 31, 1921, and No. 1,424,844, dated August 8, 1922, as also our 25 pending application Serial No. 569,646, filed June 20, 1922; the present invention providing means whereby not only will the stop motion device be rendered operative to stop the machine when a knot or lump occurs in 30 a thread, but will also stop the machine when a thread or needle breaks, as will hereinafter appear.

In the accompanying drawings Fig. 1 is a perspective view of the stop motion device 35 fully shown and described in our application No. 569,646, referred to, somewhat modified to adapt the same for use in connection with a clutch stop motion device instead of the brake stop motion device as set forth 40 in our said application. Fig. 2 is an elevation showing the present invention applied to a well-known form of sewing machine. Fig. 3 is a detail plan view of certain parts shown in Fig. 2. Figs. 4, 5 and 45 6 are detail views showing certain parts of the mechanism for operating the stop motion device when a thread breaks. Figs. 7 and 8 illustrate a modified form of the invention.

50 Referring to the drawings, 12 denotes a bracket or support which may be attached to a work bench conveniently adjacent to a

sewing machine in connection with which the improved stop motion device is to be used, said bracket having an upright 13 and 55 a standard 14 affording bearings for a rock-shaft 15 provided at its forward end, inside of upright 13, with an arm 16 carrying a plate 19 provided with a curved slot 20 entered by a pin 17 at the lower end of a 60 latch-lever 18 pivoted to said upright 13 and having a bevelled or rounded upper end adapted to be engaged by a finger 21 on a holding latch 22 fixed to a tripping rock-shaft 23 journalled in bearings afforded by 65 the upwardly projecting lugs 24 at the upper end of the upright 13.

The lower wall of the curved slot 20 is turned down sharply at one end affording a notch 20^a which receives the pin 17 when 70 the parts are in working position, said pin being moved downward into said notch, when the parts are being set for the normal operation of the machine, by the co-action of the curved upper wall of said slot and 75 the momentum of the latch lever by which said pin is carried. Thus the manual operation of the rock-shaft 15 will, by means of the slotted plate 19 engaged by the pin 17, move the arm of the said latch lever inward 80 beneath and behind the holding finger 21 on the latch 22 thereby setting the parts in the position which they will occupy when the machine is running.

The tripping rock-shaft 23, in the form of 85 the invention herein shown, carries a tripping arm 26 having a plurality of narrow slits 28 permitting the free passage of the threads but not of knots or lumps in the threads, as in the construction shown in our 90 Patent No. 1,380,003, hereinbefore referred to, so that said tripping arm will be tripped or moved downwardly slightly when engaged by a knot or lump in a thread. The slits 28 have V-shaped or inwardly tapering 95 open ends 29 which serve to facilitate the entrance of the threads in said slits, and which also serve, in conjunction with the thread guides 30 and 31, arranged on opposite sides of said tripping arm, to permit the escape of the knots or lumps from the tripping arm when the latter is moved 100 downward in the tripping operation, thereby avoiding breaking the thread by the ma-

chine, which is objectionable, even though the thread has to be broken by the attendant to remove the knot or lump.

The holding latch 22 is normally held in yielding contact with an adjustable stop-pin 32 tapped in a lug 33 on the upright 13 and held in any desired position of adjustment by a lock-nut 34. This holding of the latch 22 against the top of the pin 32 is effected by the coil spring 35 connected at its upper end to a hooked arm 36 on the rock-shaft 23 and connected at its lower end to a lug 37 on a bracket 38 adjustably attached to the upright 13 by a set screw 39 passing through a slot in said bracket.

The construction and co-relation of the holding latch 22 with its finger 21, for engaging the latch lever 18, the spring 35 and its connection with the rock-shaft 23, by which the latch 22 is carried, are the same as in the machine of our Patent No. 1,424,844, hereinbefore referred to, these parts being clearly shown in Fig. 4 of the drawings of said patent.

The construction thus far described is the same as the corresponding parts, with corresponding reference numerals, in our application No. 569,646, above referred to, and which parts are intended to render the stop motion operative to stop the machine when a lump or knot occurs in the thread, the construction now to be described serving also to render the stop motion device operative when a thread breaks.

Fixed to the rear end of the rock-shaft 15 is an arm 40 provided with a slot 41 and a padded foot piece 42. Fixed to the work bench or table conveniently adjacent to the bracket 12 is a bracket comprising a base piece 43 and uprights 44. Journalled in said uprights 44 is a rock-shaft 45 provided at one end with an arm 46 entering the slot 41 of the arm 40, said rock-shaft having at its opposite end an arm 47 to which is rigidly attached an extension 47^a having a laterally projecting arm or pin 48.

The driving shaft 49 of the sewing machine, in the construction shown, is provided with a fixed clutch wheel 50 adjacent to which is a loose pulley 51 having a pin 52 for engagement with said clutch wheel 50. Pivotally mounted on an arm 53 fixed to the base plate B of the sewing machine is a clutch-operating hand lever 54 the inner end of which is provided with an upwardly extending lug 55 adapted to be engaged by the laterally extending arm or pin 48 carried by the extension 47^a of the arm 47 on the rock-shaft 45. The arm 40 may be utilized as a setting handle in placing the stop-motion parts in the position which they will occupy when the machine is running, and in so doing the torsional coil spring 58 on the rock-shaft 15 will be given additional tension, as will be understood, one end of

said coil spring being engaged with a fixed part and the other end thereof being connected with a collar 15^a on the rock-shaft 15, and by the proper adjustment of which collar any desired tension may be given to the said torsional spring 58, thus storing up any desired amount of power in said spring to be utilized to operate the stop-motion device.

From the foregoing it will be understood that when the arm 26 is tripped, either by a lump or knot in the thread, or otherwise, the latch lever 18 will be released from the finger 21 on the latch 22, the tripping rock-shaft 23 thereby releasing the pin 17 from the holding notch 20^a at one end of the curved slot 20 on the arm 16, so that by the stress of the torsional spring 58 the rock-shaft 15 will be operated to move the arm 40 downward; thereby, through the connections just described, enabling the rock-shaft 45 to act on the clutch operating lever 54 to disconnect the loose pulley wheel 51 from the fixed clutch wheel 50, thereby stopping or arresting the movement of the driving shaft of the machine.

Suitably secured to the bracket arm A of the sewing machine, as by a clamping set screw 56, is a bracket 57 at the lower portion of which is mounted a slide 59 having a slot 59^a through which passes an arm 60 of a counterbalanced lever 61 attached to a sleeve 62^a pivoted on a fulcrum screw 62 mounted on the said bracket 57, the said lever 61 having a second arm 63 arranged to abut against the end of the slide 59. The slide 59 is provided with a stop screw 64 which, by contact with one end of the bracket 57, will limit the movement of the slide 59 when said slide is operated by the said arm 63. Attached at one end of the slide 59 is a light rod 65 extending from the said slide through the arm of the thread guide 31 and past the tripping arm 26, the said rod being provided with a hook 66 partly embracing said tripping arm.

The lever 61 carries at one end a lateral projection 61^a provided with a thread eye, and the needle thread *t* runs in the direction denoted by the arrows in Fig. 2 through the thread guide 30, the tripping arm 26 and the thread guide 31, to the thread guide 67, thence to another thread guide 68, thence through an ordinary disk tension device 69 and over a tension block 70, mounted on a rod 71 and pressed upward by a light coil spring 72 encircling the said rod 71. The thread passes from the tension block 70 through a thread-eye in the lug or projection 61^a on the lever 61, the thread running from said last-named thread-eye to a thread-eye 73, and thence to the needle of the machine. The lever 61 is preferably maintained in the position shown in Fig. 2 by a light spring 74 counterbalancing the

stress of the spring 72, (although a weight 74^b on said lever 61 may be employed instead of said spring 74) so that when the thread is passing through the thread-eye in the 5 lateral projection 61^a the parts will be maintained in the position shown in Fig. 2, but should the thread or needle break and the thread running between the needle and the tension device 69 thus be slackened or released 10 from the thread-eye in the lever 61, the equipoise of the counterbalanced lever will be disturbed and the spring 74 or weight 74^b will move down the end of the said lever opposite the said thread-eye, 15 thereby, through the arm 60, operating the slide 59 which, in turn, through the rod 65, will operate the tripping arm 26 to release the latch lever 18 from the finger 21 of the latch 22, thus enabling the torsional spring 20 58 to act, through the parts above described, to shift the clutch lever 54 and disengage the clutch parts to stop the machine.

Instead of employing the counterbalanced lever 61 and the slide 59 co-operating therewith, hereinbefore described, the simpler construction for operating the rod 65, illustrated in Figs. 7 and 8, may be employed. In this simpler construction a counterbalanced lever 61^b is attached to a 30 sleeve 62^a rotatably mounted on a stud 62^b the hub portion of said lever being provided with two depending arms 61^c and 61^d, said arms having offset projections 61^e at their lower ends. Located between said projections 61^e is the upturned rear end 65^a of the rod 65, said rear end of said rod sliding in a groove 57^a in the lower part of the bracket 57 and in which groove said rear end of said rod is free to slide. Coiled 40 around the sleeve 62^a is a light spring 74^a one end of which is connected with the lever 61^b and the other end of which is connected with a washer 75 mounted on the stud 75^b, and which washer may be secured in any 45 desired position of adjustment by means of a set nut 76. A proper tension is given to the spring 74^a by a suitable adjustment of the washer 75, so that the lever 61^b is counterbalanced by the stress of said spring, 50 under ordinary conditions, but if the thread or needle breaks the said lever will be lifted by said spring and the arm 61^c of said lever will draw the rod 65 rearward to trip the arm 26, as in the construction hereinbefore described. With this simpler construction 55 the lever 61^b will serve, to a certain extent, as a take-up lever, there being considerable play between the off-set projections 61^e and the upturned rear end 65^a of the rod 65, and the thread will run directly from the tension device 69 to the thread eye in the part 61^a and thence forward to the needle.

From the foregoing it will be understood that the present invention provides means 65 not only for stopping the machine when a

knot or lump occurs in a thread, but also when a thread or needle breaks, and the thread engaging the thread eye on a counterbalanced lever, as 61 or 61^b, thus be slackened.

It will be understood that the present invention may be utilized with other thread-using machines than sewing machines, as knitting machines or the like, for the purpose of stopping the machine when a lump or knot occurs in a thread or when a thread is slackened by the breaking of a thread or needle; and it will also be understood that the invention may be utilized in connection with a brake stop-motion device or a belt shifter stop-motion device, as well as with a clutch stop-motion device, these different forms of stop-motion devices being well-known mechanical equivalents. The invention is therefore not to be considered as being limited to the special constructions shown, as the invention, as defined by the claims hereunto appended, may be varied widely, within the province of mechanical skill, without departing from the essence or scope of the invention.

Having thus described our invention, we claim and desire to secure by Letters Patent:

1. The combination with the driving shaft 95 of a thread-using machine, of a stop-motion device for said shaft, and tripping means for controlling said stop-motion device to stop the machine when a thread or needle breaks, as also when a knot or lump occurs in the thread, said tripping means comprising a slotted tripping arm and a member controlled by tension on the thread and operatively connected with said tripping arm.

2. The combination with a driving shaft 100 of a thread-using machine, of a spring-controlled rockshaft, holding means for said rockshaft, means, comprising an apertured tripping arm through which the thread will normally pass freely, but which will be tripped by a knot or lump in the thread, said tripping arm, when operated, serving to release said holding means, a stop-motion device, and a thread-controlled member 110 connected with said tripping arm and held in normal position by tension on the thread, said member acting on said tripping arm, when the thread is slackened, to release said holding means and thereby render the stop-motion device active to arrest the movement of said driving shaft; whereby the machine will be stopped either by a knot or lump in the thread, or by the breaking of the thread or needle.

3. The combination with the driving shaft 115 of a thread-using machine, of a spring-controlled rockshaft, holding means for said rockshaft, means, comprising an apertured arm through which the thread will nor-

mally pass freely, but which will be tripped by a knot or lump in the thread, said tripping arm, when operated, serving to release said holding means, a stop-motion device, and a thread-controlled lever held in normal position by tension on the thread, said lever being connected with said tripping arm, and serving, when the thread is slackened, to release said holding means and

thereby render the stop-motion device active to arrest the movement of said driving shaft, whereby the machine will be stopped either by a knot or lump in the thread, or by the breaking of the thread or needle. 10

In testimony whereof we affix our signatures. 15

WILLIAM S. MILLS.
HECTOR E. BISAILLON.
